TYPEWRITER

Max Pfau, Frankfort-on-the-Main, Germany, assignor to Torpedo-Werke Aktiengesellschaft, Frankfort-on-the-Main, Germany

Application April 2, 1937, Serial No. 134,537
In Germany July 3, 1936

8 Claims. (Cl. 197—186)

The invention relates to typewriters, particularly to portable and small typewriters, in which the type mechanism and the inking ribbon spools are covered by a protecting hood, and has for one of its objects the provision of means for securing the said protecting hood to the frame of the machine in such manner that for the purpose of replacing the inking ribbon, cleaning the types or the like, the protecting hood may be removed or swung open without the aid of tools, but is nevertheless securely held on the frame of the machine during use.

For this purpose, the protecting hood according to the invention is secured to the machine frame by means of spring clip connections and a sliding bolt connection, the spring clip connections being provided on the side which faces the carriage, and consisting of hinge pins mounted between spring tongues on the machine frame, so that the protecting hood may be swung open in the direction of the roller or platen when said bolt connection arranged on the front of the frame has been disengaged.

By reason of this particular method of securing, the protecting hood may either be swung open, which is sufficient, for example, for replacing the inking ribbon, or completely removed from the frame without difficulty.

In order to prevent the protecting hood from being lifted while the line spacing lever or any other part of the carriage of the machine is lying in the path of the protecting cover, said bolt is provided with a locking device which is so controlled by the carriage that said bolt cannot be disengaged until the carriage takes up a position in which the line spacing lever lies adjacent the frame of the machine.

In order that the said invention may be clearly understood and readily carried into effect, the same will now be described more fully with reference to the accompanying drawings, in which,

Figure 1 is a plan view of the frame of a small typewriter,

Figure 2 is a side elevational view partly in section,

Figures 3 to 5 show details of the spring clip connections,

Figures 6 and 7 are side elevational and plan views respectively of the sliding bolt,

Figures 8 and 9 are rear elevational and plan views respectively of the locking device for the bolt, and

Figure 10 shows a modified form of spring clips employable in the invention.

The frame 1 of the machine is of usual con-

struction and comprises a front wall 2 and side walls 3, the carriage 5 being displaceable on a roller guide 4 (Fig. 2). A protecting hood 6 recessed for the passage of the type levers serves to cover the mechanism of the machine and the inking ribbon spools thereof.

The machine frame 1 has brackets 7 which are screwed to the side plates 31, and which carry two pairs of spring clips 8, 9 (Figures 3 to 5), lying in front of the roller or platen 10 and 12 forming hinges for pins 11 arranged on the rear edge of the protecting hood 6. The protecting hood 6 is thus so held as to be easily swingable about the spring clips 8, 9, while it may be easily withdrawn from said spring clips by pulling said hood in an upward direction.

Under the inwardly bent edge 12 (Figures 6 and 7) of the front wall 2 of the machine frame 1, a locking lever 14 is mounted to pivot about a pin 13 against the action of a torsion spring 15. The push button 16 is placed at an end of the locking lever 14 which passes through the front wall 2 of the machine frame 1, the lever having under its extremity 17 a downwardly bent part provided with a cam edge 19. The extremity 17 is adapted to engage over the stop hook 29 attached to the hood 6 in any convenient manner.

On an extension 20 of one of the brackets of the spring clips 8, 9 a lever 21 is mounted to pivot about a pin 22, a downwardly bent part 24 of a locking bar 25 being guided in an oblique slot 23 in the said lever 21. The locking bar 25 is rotatably mounted close to one side wall of the machine frame and has a laterally disposed arm 26 which extends under the edge 12 of the front wall 2 to a point adjacent the cam edge 19 of the lever 14.

The laterally disposed parts of the locking bar 25, and also the pivoted lever 21 with the slot 23 are of such dimensions that the pivoted lever 21 may lie together with a projection 27 in the path of a control strip 28 or the carriage 5. Under the action of the weight of the laterally disposed arm 26, the projection 27 will normally occupy the position such that it lies in the path of the strip 28, and the arm 26 will occupy its lowest position as shown in full lines in Figures 6, 8 and 9. In this position the arm 26 is clear of the cam edge 19 and allows movement of the lever 14.

If, however, the carriage 5 is lying in such a position as to engage the pivoted lever 21 with the strip 28, then the arm 26 of the locking bar 25 assumes the upper position (shown in dotted

lines) illustrated in Figures 6 and 8 and bears against the cam edge 19 of the locking lever 14. The latter is then prevented from swinging about its pivot 13, so that it cannot leave the hook 29 and therefore cannot release the hood 6. The projection 27 is not released from engagement with the control strip 28 of the carriage of the machine until the line spacing lever 30, which moves over the protecting hood 6 during a part 10 of the movement of the carriage, has reached a position to one side of the hood and consequently would no longer jam against said hood on opening or removal thereof. The carriage 5 must therefore be moved so far to the left, before the 15 opening of the protecting hood 6, that the line spacing lever 30 is no longer located immediately above the protecting hood. The control strip 28 then allows the arm 26 to fall and release the locking lever 14.

20 The two spring clips 8, 9 shown in Figure 4 may be constructionally modified. For example, the clip part 32 (Figure 10) may be of rigid material and have a curved portion 33 completely receiving the pin 11, a flat leaf spring 34 bearing 25 against the said curved portion.

It will be noted from the above explanation that there is thus provided in a typewriter having a frame, a carriage on said frame, type mechanism, ink ribbon spools for said mechanism, and a protecting hood for said mechanism and said spools, a part of said carriage being movable over said hood, the combination of hinge means to connect said hood with said frame on one side of said frame, connectable means for said frame 30 and said hood on the opposite side of said frame, and arresting means adapted for engagement with a movable part of said connectable means, and means under control of said carriage for placing said connectable means under restraint 35 by said arresting means only when said part of said carriage is positioned above said hood.

What I claim is:

1. In a typewriter having the type mechanism and the inking ribbon spools covered by a protecting hood, pairs of spring tongues arranged adjacent the platen upon the frame of the machine, pivot members secured to the hood and adapted to detachably and rotatably enter between the spring tongues, a sliding bolt connection between 40 the front side of said hood and the front side of the machine frame, a member disposed within the path of the carriage of the typewriter, and a connection from said member to a locking element arranged adjacent the said sliding bolt 45 and adapted to impede the action of the same when said member and carriage co-act with one another.

2. In a typewriter having the type mechanism and the inking ribbon spools covered by a protecting hood, spring clip connections adjacent the platen between the rear side of said hood and the adjacent part of the machine frame, a sliding bolt connection at the front side of said hood between the latter and the adjacent part 50 of the machine frame, a member pivoted at one end and having its other end arranged to lie in the path of the carriage of the typewriter, a mechanical connection between the free end of said member and a locking element, and a cam edge connected with the slidable bolt of said sliding bolt connection, whereby displacement of said pivoted member by co-action with the carriage results in movement of the locking element 55 to an engaged position with the cam edge to prevent movement of the sliding bolt.

3. In a typewriter having the type mechanism and the inking ribbon spools covered by a protecting hood, spring clip connections between the hood and frame along the side of the hood adjacent the platen, a sliding bolt connection between the hood and frame at the front side thereof, a pivoted member having its free end arranged to lie in the path of the typewriter carriage, a bar connected to said free end and extending in front of a cam edge secured to the bolt of said sliding bolt connection, said bar being shaped so that when the pivoted member co-acts with the carriage the portion of the bar in front of said cam edge lifts to a position where the latter is locked against movement. 15

4. In a typewriter having a frame, a carriage on said frame, type mechanism, ink ribbon spools for said mechanism, and a protecting hood for said mechanism and said spools, a part of said carriage being movable over said hood, the combination of hinge means to swingably and clampingly connect said hood with said frame on the rear side of said frame, connectable means for said frame and said hood on the front side of said frame and said hood, and locking means adapted to engage said connectable means, said locking means being controllable by said carriage, said connectable means being releasable from said locking means when said part of said carriage is removed from above said hood. 20

5. In a typewriter having a frame, a carriage on said frame, type mechanism, ink ribbon spools for said mechanism, and a protecting hood for said mechanism and said spools, a part of said carriage being movable over said hood, the combination of hinge means to connect said hood with said frame on one side of said frame, connectable means for said frame and said hood on the opposite side of said frame, and arresting means adapted for engagement with a movable 25 part of said connectable means, and means under control of said carriage for placing connectable means under restraint by said arresting means only when said part of said carriage is positioned above said hood. 30

6. In a typewriter having a frame, a carriage on said frame, type mechanism, ink ribbon spools for said mechanism, and a protecting hood for said mechanism and said spools, the combination of hinge means at the rear of said hood and said frame, movable connectable means for said frame and said hood mounted at the front of said frame, said hinge means and said connectable means detachably retaining said hood on said frame, and means controllable by carriage position and engageable with said connectable means for impeding movement of said connectable means at predetermined positions of said carriage. 45

7. In a typewriter having a frame, a carriage on said frame, type mechanism, ink ribbon spools for said mechanism, and a protecting hood for said mechanism and said spools shiftable to expose ribbon spools and type mechanism; first means adjacent said carriage connecting said hood to said frame, second means releasably connecting said hood to said frame at the opposite end of said hood, and means controllable by carriage position and engageable with said second connecting means for arresting releasing action of said second connecting means when said carriage is in a position to obstruct the shifting of said hood. 50

8. In a typewriter, a frame, a carriage on said frame, a platen mounted on said carriage, type 55

mechanism and ink ribbon spools in front of said platen and covered by a protective hood; a hinge connection between said hood and said frame adjacent said platen, a sliding bolt connection between the front side of said hood and the front side of said frame, a member disposed within the path of said carriage and arranged

to be shifted thereby, an element secured to a sliding part of said bolt connection, and means connected to said member and extending to said element and shiftable to a position to impede the action of said slideable part when said member and carriage coact with one another.

MAX PFAU.
